(57) **CLAIM**

(21) Appl. No.: **29/309,757**

The ornamental design for an air conditioning device, as
shown and described.

(22) Filed: **Oct. 6, 2008**

DESCRIPTION

(30) **Foreign Application Priority Data**

Apr. 8, 2008 (IL) 45809

FIG. 1: Perspective view of the air conditioning device;

(51) **LOC (9) Cl.** **23-04**

FIG. 2: Front view thereof;

(52) **U.S. Cl.** **D23/351**

FIG. 3: Left side view thereof;

(58) **Field of Classification Search** D23/351-354;
312/236; 62/259.1, 259.4, 262-263, 304;
454/330-331, 349-350

FIG. 4: Right side view thereof;

See application file for complete search history.

FIG. 5: Top plan view thereof; and,

(56) **References Cited**

FIG. 6: Bottom plan view thereof.

U.S. PATENT DOCUMENTS

The back of the air conditioning device is flat and unornamented and is mounted on the wall or other support.
